United States Patent Office

Des. 178,594
Patented Aug. 28, 1956

178,594

CARPORT OR SIMILAR ARTICLE

Carroll W. Clement, Pueblo, Colo.

Application December 1, 1955, Serial No. 39,121

Term of patent 14 years

(Cl. D13—1)

Fig. 2

Fig. 3

Figure 1 is a fragmentary perspective view of a carport or similar article, showing my new design with portions broken away for convenience of illustration;

The dotted lines in Figures 2 and 3 are for illustrative purposes only.

I claim:

The ornamental design for a carport or similar article, as shown and described.
